UNITED STATES PATENT OFFICE

155,324

DESIGN FOR AN EGG OPENER

Fritz von Hirsch, Nutley, N. J.

Application May 14, 1947, Serial No. 139,028

Term of patent 14 years

(Cl. D44—29)

To all whom it may concern:

Be it known that I, Fritz von Hirsch, a citizen of the United States and a resident of Nutley, in the county of Essex, State of New Jersey, have invented a new, original, and ornamental Design for an Egg Opener, of which the following is a specification, reference being had to the accompanying drawing, forming a part thereof.

In the drawing,

Figure 1 is a top plan of the egg opener showing my new design in a closed position;

Figure 2 is a bottom plan of the egg opener in a closed position;

Figure 3 is a top plan of the egg opener in an open position; and

Figure 4 is an edge view of the opener shown in Figure 1.

I claim:

The ornamental design for an egg opener, substantially as shown and described.

FRITZ VON HIRSCH.
